LIQUID LEVEL GAUGE

Edward H. Kocher, Boonton, N. J., assignor to
Auto Research Corporation, a corporation of
Delaware

Application July 16, 1940, Serial No. 345,769

9 Claims. (Cl. 73—334)

The present invention relates to oil window constructions and it particularly relates to window constructions which may conveniently be positioned in the side walls of reservoirs utilized in and about machinery to supply lubrication to a centralized lubricating system.

It is among the objects of the present invention to provide and include an improved oil window assembly which may be readily fitted into a wall or socket in the side wall of an independent or integral reservoir construction, and which will require minimum of handling and work by the workman or customer who makes the assemblage.

Still further objects and advantages will appear from the more detailed description set forth below, it being understood, however, that this more detailed description is given by way of illustration, since various changes therein may be made by those skilled in the art without departing from the scope and spirit of the invention.

In accomplishing the above objects, it has been found most satisfactory to provide a ring-like holder member designed to be press-fitted into a socket or recess inside of a reservoir. This ring member may receive or frame a transparent panel, preferably of a synthetic plastic material resistant to oil, as for example, a synthetic transparent phenol formaldehyde resin or a urea formaldehyde resin.

The same ring may also hold or frame a backing member, for example, of a contrasting color so as to clearly show the oil level, and most desirably of aluminum.

In the drawings, which illustrate one of the various embodiments of the present invention but to which the invention is by no means specifically limited,

Fig. 1 is a side section view of a reservoir including a small pump, together with one of the oil windows in position upon the line 1—1, of Fig. 2;

Fig. 2 is a side elevational view from the line 2—2 of Fig. 1;

Fig. 3 is an exploded or separated side perspective view upon an enlarged scale as compared to Figs. 1 and 2, showing the elements of the oil window before assembly;

Fig. 4 is a fragmentary side sectional view similar to Fig. 1, of an alternative oil window assembly inserted in the side of the reservoir;

Figs. 5, 6, and 7 are respectively side sectional views of alternative oil window assemblies in the side of a reservoir construction;

Fig. 8 is a side perspective view of the tool

which may be utilized for inserting the oil window assemblies in position.

Referring to Figs. 1 and 2, the reservoir 10 may be made of cast aluminum or iron and may constitute a separate unit for part of a machine to be provided with a centralized lubricating system.

The reservoir 10 may be mounted by the tapped sockets 11, and it is provided with a cover 12 having the dome 13 with the removable cover plate 14.

The pump P has a body or cylinder member 15, a reciprocating piston 16, an inlet filter 17 and an outlet connection 18. The pump body 15 is suspended by the bracket 19, which is held in position by the nut 20 screwed upon the upper threaded portion 21 of the pump body.

The outlet connection 18 continues in the tube 24 which leads to the outlet nipple 25 on the cover 12 (see Fig. 2), and is provided with an outlet coupling connection 26 to the tubing 27.

The side of the dome 13, which is of square or rectangular shape, is provided with a bearing for the shaft 28. The shaft 28 receives the eye 29 of arm 31 pinned in position at 30. The forward end 32 of the arm 31 takes the form of a clevis which fits around the sleeve 33 on the reduced diameter portion 34 of the piston 16 which projects above the cylinder or body member 15.

The outer end of the shaft 28 carries the lever 35 with the finger press portion 36.

The stroke of the piston 16 and reciprocation of the lever 35 is determined by the adjustable screw member 38 which has a threaded shank 39 held in adjusted position by the nut 40. The threaded shank 39 extends through a tapped opening (not shown) in the cover 12.

The cover of the reservoir is also provided with an opening 41 which receives the open cup member 42 having the snap cover 43 to enable filling of the reservoir 10.

The lever 35 is normally biased in the direction 44 by the spring 45 (see Fig. 1).

This pump and reservoir construction which is more fully covered in application Serial No. 267,372, filed April 12, 1939, does not form the primary part of the present invention.

The present invention is particularly directed to the window assemblage A, and may be used with other reservoir constructions, as for example, those described and illustrated in copending applications of Edward H. Kocher, Serial Nos. 745,187, filed August 24, 1934, issued as Patent No. 2,229,095, granted January 21, 1941; 30,462, filed July 9, 1935, issued as Patent No.

2,229,096, granted January 21, 1941; and Patent No. 2,145,245, issued January 31, 1939.

The oil window assemblage to which the present invention is most particularly directed, consists of a shell 50, a window 51, preferably of a transparent synthetic oil resistant plastic, such as Lucite, a gasket ring 52 and a backing plate or cup 53 of a contrasting color material. The cup 53 has a flange 61, a rearward extending cylindrical portion 62 and a base 63. The base 63 is perforated desirably by being provided with openings 64 so that the lubricant may enter the space 65 between the base 63 and the glass 51. Cup 53 will show up the oil level and may be made of aluminum or chromium plated steel, or even of a white plastic material which is not transparent.

As shown best in Fig. 1, the side 54 of the reservoir 10 is provided with an opening 55 into which the face 56 of the ring 50 is designed to be press fitted.

The recessing 57 of the ring 50 enables more ready insertion of the assemblage and the extension of the ring may be turned inwardly at lip or rim 58 of reduced thickness to force the window 51, the gasket 52 and the cup 53 against the shoulder 60.

The ring 52 may be made of any compressible material, such as Vellumoid, resinol, or neoprene which will be oilproof, and it will be tightly compressed between the flange 61 of the cup 53 and the window 51. If desired, an additional gasket (not shown) like gasket 52 may be utilized between the window 51 and the shoulder 60.

The assemblage as shown upon Fig. 1 at A, may be made prior to insertion in the opening 55 with or without the cup 53, and such oil window assemblies may be sold ready for insertion in position. The assemblage A is inexpensive, may be readily forced in position and by utilization of the contrasting color base portion 63 of the cup 53 gives immediate indication of the oil level.

In the embodiment of Figs. 1, 2 and 3 (and in the embodiments of Figs. 4, 5, 6 and 7 herein-after described) it will be seen that the perforated backing member in combination with the mounting ring constitutes a perforated cup and that the contained elements including the window member and one or more gaskets are clamped in position between the base of the cup and an inturned flange.

In the alternative construction shown in Fig. 4 (similarly functioning parts being indicated by the same numerals primed), the ring 50' is threaded at its face 56' and is screwed into the tapped opening 55' by application of a tool to the openings 70. The threads 55' and 56' may desirably be pipe threads so as to assure a relatively lubricant-tight connection.

In the embodiment of Fig. 5 (similarly functioning parts being indicated by the same numerals provided with a superior 3), the cup 53³ is formed integral with the ring 50³ and the gasket 52³ is pressed between the edge of the window 51³ and the offset perimeter portion 74 of the base 63³ of the cup element 53³. The in-turned rim 80 of the cup clamps the gasket 81 against the rim of the outer face of window 51³.

In the embodiment of Fig. 6 (similarly functioning parts being indicated by the same numerals provided with the superior 4), the pre-assembled unit A⁴ may carry the exterior gasket 75 which encircles the reduced diameter portion 76 of the ring 50⁴. The gasket 75 is pressed

against a shoulder 77 in the side wall of the reservoir by the flange 78 which flange fits in the enlarged diameter portion 79 of the socket in the side of the reservoir.

5 The press fit takes place in the construction of Fig. 6, along the face 76 and there is no press fit along the face 79.

10 The face of the ring 50⁴ which may be polished, is flush with the side of the reservoir. It will be noted in the construction of Fig. 6, that the gasket 75, the ring 50⁴, the gasket 52⁴ and the cup 53⁴ may all be assembled in one piece and handled as a single unit for assembly purposes. To this end the rim of cup 53⁴ abuts against a 15 shoulder 65⁴ in ring 50⁴ and the inner rim of said ring is turned over at 66⁴ to clamp the cup 53⁴ in place.

15 In the embodiment of Fig. 7 (similarly functioning parts being indicated by the same numerals provided with the superior 5), the press fit here takes along the outer socket face 79⁵ with the gasket 75⁵ being pressed against the shoulder 77⁵. The ring 50⁵ may be made of brass with a polished face which will be flush with the wall of the reservoir.

20 It will be noted in both embodiments of Figs. 6 and 7, the entire assembly is made liquid tight in respect of the reservoir by a press fit and a gasket 75 and 75⁵ while the windows 51⁴ and 51⁵ are made lubricant tight by the interior gaskets 52⁴ and 52⁵ respectively.

25 These window assemblies may vary in size from 1 to 2 inches and preferably are of either 1 1/8 or 1 1/2 inches in size with a window opening of about 1 to 1 1/8 inches. The metal rings may be made of aluminum, brass or iron, the latter if used being preferably chromium plated.

30 In the embodiment of Fig. 6, it is possible to ream the hole 76 for the press fit right through the wall of the reservoir while the outer flange 78 and gasket 75 are in a clearance pocket 79.

35 In the embodiment of Fig. 7, the press fit is located at 79⁵ on the outside of the gasket 75⁵ which is a little harder to hold to size than if 40 the reamed hole goes straight to the inner wall of the reservoir as in Fig. 6.

45 The tool, as indicated in dot and dash lines in Fig. 6 and in perspective in Fig. 8, has a hexagonal or octagonal handle member 100 with the conical end portion 101, to which a hammer may be applied. It also has the hood 102 which has a face 103 to be pressed against the outer face of the side wall 54. The projecting portion 104 is designed to fit inside of the ring 50. The face 55 103 will press the ring 50 into position so that it will be flush with the exterior face of the wall 54.

50 It will be understood that many changes could be made in the particular features of oil window construction as shown, and many apparently widely different embodiments of this invention could be made without departing from the scope of the claims and it is intended that all matter contained in the above description or shown in the accompanying drawings shall be interpreted as illustrative and not in a limiting sense.

55 60 65 70 75 What is claimed is:

1. As a preassembled oil window construction, a cup structure having a perforated base, a cylindrical side wall and presenting an inturned rim 70 at its forward face and formed on its exterior periphery so as to be fitted in oil tight fashion in an opening in the side wall of a reservoir, the entire thickness of said window assembly being substantially accommodated within the thickness of said side wall and a plurality of elements ac-

commodated within said cup structure and including a window member and a gasket ring of diameter equal to the maximum inner diameter of said cup structure and peripherally engaging the side wall thereof and collectively engaging and clamped in place between the perforated base and the inturned rim of the cup structure.

2. As a preassembled oil window construction, a mounting ring formed on its exterior periphery so as to be fitted in oil tight fashion in an opening in the side wall of an oil reservoir, the entire thickness of said window assembly being substantially accommodated within the thickness of said side wall, said ring being interiorly shouldered and recessed, a plurality of elements each with an outer rim engaged by and accommodated within said recessed and shouldered portion of the mounting ring and including a window member and a perforated backing member defining an oil chamber therebetween, and within said mounting ring, said ring having an integral extension lip clamped against that element accommodated within said ring which is contiguous to said lip.

3. A preassembled oil window construction for insertion in the side walls of lubricant-containing reservoirs, comprising a cylindrical ring member, a window member of diameter equal to the maximum inner diameter of said ring member and which is encompassed and engaged by said ring member, said window member being constructed of a transparent, oil resistant synthetic plastic material, and a perforated rear cup member of diameter equal to that of said window member and extending across said window member for purposes of enhanced visibility of the oil level, said ring member, window member and cup member being formed as a unitary assemblage and being clamped together by an in-turned, integral, reduced thickness rim from one side of said ring member.

4. A preassembled disk-shaped oil window construction comprising, a mounting ring formed on its exterior periphery to be fitted in oil tight fashion in an opening in the side wall of an oil reservoir, the entire thickness of said window construction being substantially accommodated within the thickness of said side wall, said ring having an inturned flange at its forward portion, a window member within said ring and against said flange, a gasket member against said window member, a perforated backing plate against said gasket member, said ring having an integral rim turned inward over said backing plate.

5. The combination recited in claim 4 in which the backing plate is dished, the main inner area thereof being spaced from said window by at

least the distance between said window and said inwardly turned rim.

6. A preassembled disk-shaped oil window construction comprising a mounting ring formed to be fitted at its periphery in oil tight fashion in an opening in the side wall of an oil reservoir, the entire thickness of said window construction being substantially accommodated within the thickness of said side wall, said ring having an inturned flange near its forward portion, a window member against said flange, a gasket against said window member, a perforated backing plate against said gasket, said ring having a shoulder accommodating the rim of said plate, the rear edge of said ring being turned inward over said plate to maintain the parts assembled.

7. A preassembled disk shaped oil window construction comprising a mounting ring formed to be fitted at its periphery in oil tight fashion in an opening in the side wall of an oil tight reservoir, the entire thickness of said window construction being substantially accommodated within the thickness of said side wall, said ring having an out-turned flange at its forward face, a gasket encircling said ring and adapted to be compressed against a corresponding shoulder in said opening in the side wall of an oil reservoir, said ring having an inturned flange near its forward face, a window member within said ring against said flange, a gasket within said ring against said window member, a perforated backing plate within said ring against said gasket, the rear edge of said ring being turned inward over said backing plate.

8. A preassembled disk-shaped oil window construction comprising a unitary perforated mounting cup formed for its entire exterior periphery to be fitted in oil tight fashion in an opening in the side wall of an oil reservoir, a window member within said cup, gasket means within said cup associated with said window, the base of said cup being at the inner face of said oil reservoir, the rim of said cup at the outer face of said reservoir being turned over to assemble the contained parts therewith.

9. In an oil window construction to be inserted in oil tight fashion in an opening in the side wall of an oil reservoir, a ring formed on its exterior periphery so as to be fitted in oil tight fashion in said opening, said ring having an integral extension lip of reduced thickness from one side thereof and being interiorly shouldered and recessed, and a window member, a gasket ring and a perforated backing cup fitted into and clamped into said recessed and shouldered portion of the ring by inturning of said lip.

EDWARD H. KOCHER.
